US00D930001S

(12) **United States Design Patent** (10) **Patent No.:** **US D930,001 S**
(45) **Date of Patent:** **** Sep. 7, 2021**

(54) **CARD**

(71) Applicant: **HUAWEI TECHNOLOGIES CO., LTD.**, Shenzhen (CN)

(72) Inventor: **Jiangtao Yang**, Shenzhen (CN)

(73) Assignee: **HUAWEI TECHNOLOGIES CO., LTD.**, Shenzhen (CN)

(**) Term: **15 Years**

(21) Appl. No.: **29/658,383**

(22) Filed: **Jul. 31, 2018**

(30) **Foreign Application Priority Data**

Feb. 1, 2018 (CN) 201830049545.0

(51) **LOC (13) Cl.** **14-02**

(52) **U.S. Cl.**

USPC **D14/437**; D14/436

(58) **Field of Classification Search**

Primary Examiner — Susan Moon Lee

(57) **CLAIM**

The ornamental design for a card, as shown and described.

DESCRIPTION

FIG. 1 is a front view of a first embodiment of a card showing my new design; and,

FIG. 2 is a front view of a second embodiment of a card showing my new design.

The rear, top, bottom, left side, and right side views are omitted and form no part of the claimed design.

1 Claim, 2 Drawing Sheets
